United States Patent Office

Des. 217,726
Patented June 2, 1970

217,726

TOY TRUCK OR SIMILAR ARTICLE

Irwin Cohn, 746 West St., Leominster, Mass. 01453

Filed Nov. 12, 1968, Ser. No. 14,405

Term of patent 14 years

Int. Cl. D21—02

U.S. Cl. D34—15

FIG. 1 is a bottom, front perspective view of toy truck or similar article showing my new design;

FIG. 2 is a rear top perspective view thereof; and

FIG. 3 is a cross-sectional view taken on line 3—3 of FIG. 2.

I claim:

The ornamental design for toy truck or similar article, as shown.
